UNITED STATES PATENT OFFICE

146,129

DESIGN FOR A PAPERWEIGHT OR SIMILAR ARTICLE

Renard M. Blackhall and Maurice Kaufman,
Chicago, Ill.

Application April 10, 1946, Serial No. 128,444

Term of patent 14 years

(Cl. D74—12)

To all whom it may concern:

Be it known that we, Renard M. Blackhall and Maurice Kaufman, citizens of the United States, residing at Chicago, in the county of Cook and State of Illinois, have invented a new, original, and ornamental Design for a Paperweight or Similar Article, of which the following is a specification, reference being had to the accompanying drawing, forming a part thereof, in which

Figure 1 is a front perspective view of a paperweight embodying our new design, and

Fig. 2 is a side elevational view of the same.

We claim:

The ornamental design for a paperweight or similar article, substantially as shown.

RENAUD M. BLACKHALL.
MAURICE KAUFMAN.
